UNITED STATES PATENT OFFICE

92,937

DESIGN FOR A COMBINED MIRROR AND CLOCK

Edgar L. Vail, New York, N. Y., assignor to Jaeger Watch Co., Inc., New York, N. Y., a corporation of New York

Application April 29, 1933, Serial No. 47,939

Term of patent 14 years

To whom it may concern:

Be it known that I, EDGAR L. VAIL, a citizen of the United States, residing in the city, county, and State of New York, have invented a new, original, and ornamental Design for a Combined Mirror and Clock, of which the following is a specification, reference being had to the accompanying drawing, forming part thereof.

Fig. 1 is a face view of a combined mirror and clock showing my new design; and

Fig. 2 is a side elevation of the same.

I claim:

The ornamental design for a combined mirror and clock substantially as shown.

EDGAR L. VAIL.
